Application June 21, 1937, Serial No. 149,329

4 Claims. (Cl. 209—112)

The present invention relates particularly to means for separating foreign material such as clods of earth from food products, such as prunes and nuts, when a mixture of the two is gathered from the ground.

It is one object of the present invention to provide means for separating fleshy fruits such as prunes from foreign material picked up therewith without puncturing the skins of the fruit or otherwise mutilating or injuring the same.

It is another object of the invention to provide means that will accurately and efficiently separate rounded bodies, such as fresh prunes, from all other material having a surface conformation such as to interfere with its free rolling.

It is also an object of the invention to provide means of the character indicated that will be economical to manufacture, simple in form and construction, strong, durable, positive in operation, and highly efficient in its practical application.

In the drawings:

Figure 1 is a plan view of a portion of a machine embodying my invention.

Figure 2 is a detail elevation of a portion of the driving mechanism of the machine.

Figure 3 is a sectional view on line 3—3 of Figure 1 with parts broken away.

Figure 4 is a perspective view of a portion of the transferring device.

Figure 5 is a perspective view of a portion of one of the retarding elements and its mounting.

The supporting framework of the structure is indicated generally by the reference character 1, the top rails on the side being disposed at an angle to a horizontal plane as shown at 2.

Disposed on the upper end of the frame 1 through the medium of bearings 3 and rollers 4, is a travelling belt 5. This belt is moved in the direction indicated by arrow 6, and is inclined laterally to lie in a plane parallel with the plane of the top of the frame whereby material will roll off of the same in the direction indicated by arrow 7. The supporting platform 8 underlying the belt is provided with a flexible lip at 9 overhanging its lower edge.

At 10 is shown a transfer device paralleling the lower edge of the belt and journaled on the frame at 11. This device is formed of crossed plates 12 and 13 forming pockets 14, 14a, 14b, 14c closed at the ends as at 15. Extending lengthwise over each pocket is a shield as at 16, 16a, 16b, 16c, each side edge of the shield being spaced from the adjacent cross-plate to form the elongated passages 17, 17a, 17b, 17c, 17d, 17e, 17f, 17g. This

device is so positioned relative to the belt 5 and lip 9 that when rotated upwardly with respect thereto until one of the cross-plates 12 aligns with the top surface of the belt support the lip will fall flat upon the cross-plate and material may 5 flow freely into the pocket presented. When the device is rotated to bring the next pocket into use the lip will cover the succeeding elongated passage therein and slide over the shield until the next passage is reached, the shield and lip 10 cooperating to prevent movement of material off of the side of the belt until the desired passage is reached. If the material is discharged on to the belt at one end as at 18 then these parts cooperate with the moving belt to distribute the material 15 lengthwise of the lip ready for discharge into a pocket in the transfer device.

Upon each end of the shaft carrying the transfer device 12 is mounted a four-point star wheel as 19 by means of which the device is rotated a 20 one-quarter turn at desired intervals to bring the passages 17, 17b, 17d and 17f successively into operative receiving position.

At 20 is shown a trap-door lying substantially in the plane of the belt 5 and mounted on a 25 transverse shaft 21 near its upper end. The shaft 21 is journaled in bearings 22 on frame 1 and extends beyond the sides of the frame at each end to terminate in upwardly extending arms 23. The door is resiliently supported in the position 30 described by means of a spring 24 connected thereto and to the frame as shown.

In the present instance three other doors are mounted in the plane of the first door 20, and in the same manner as indicated at 25, 26, 27, 28, 35 29; 30, 31, 32, 33, 34; and 35, 36, 37, 38, 39.

A hopper 40 is provided below the lower edge of the lowermost door 35.

On each side of the frame 1 are mounted up-standing brackets as 41 in which are journaled 40 shafts as at 42 and 43 carrying sprocket wheels as 44—45. On each pair of sprockets is mounted a drive chain 46, and on each chain are mounted spaced fingers as 47 adapted to engage the star wheel and rotate it a one-quarter turn.

Mounted upon the chain 46 are other laterally directed and spaced fingers as 48 adapted to engage arms 23, 28, 33 and 38 in succession. These fingers are placed substantially midway between the fingers 47 so that the top door 20 is 50 swung open while the transfer device is being turned.

At 49 are shown a number of spaced plates mounted on the two chains 46 at their opposite ends as at 50. These plates extend the full 55

length of the doors and of course pass over them in the direction indicated by arrow 51, their lower edges passing close to the doors, or sliding over them. The plates 49 are spaced as the 5 fingers 47 but somewhat in advance of them as shown.

The sprocket 45 is rotated by means of a gear 52, on shaft 42 which meshes with a pinion 53 on shaft 54, the shaft 54 being driven by any 10 suitable means not shown. There is also a gear drive 55 between the shaft 54 and roller 4 whereby the belt may be operated continuously with the other mechanism.

When the machine is in operation a mixture 15 of prunes, say, and clods of earth, dirt and other foreign matter is flowed on to the belt from the chute 18, the round prunes rolling down to the transfer device and a large percentage of the foreign material being carried 20 along by the belt and discharged over its outer end.

When the transfer device is rotated a quarter turn as above described all of the material collected in a pocket is discharged upon the top 25 trap-door 20. If any material does not leave the pocket it is discharged to the ground upon the next rotative movement of the device.

Immediately before the material is discharged upon the door 20 one of the plates 49 reaches a 30 point thereover and slows down the movement of the flowing material so that earth clods and almost all of the material that is not as round as the prunes will find a flat side and stop. But as the plate moves on the prunes and some of 35 the rounder debris will follow it until it reaches the next succeeding door 25. When this point is reached a finger 48 engages the arm 23 of door 20 and swings it down into the position 20a, thereby dumping all of the material thereon 40 to the ground, the spring 24 returning the door to its original position as soon as the finger 48 has passed over arm 23.

The above described steps are repeated on doors 25, 30 and 35 with the result that all of 45 the foreign matter is removed by the time the prunes roll off of the last door into the hopper 46.

It is to be understood of course, that while I have herein shown and described but one specific embodiment of my invention, changes in form, 50 construction, and method of assembly and operation may be made within the scope of the appended claims.

I claim:

1. A separator of the character indicated comprising, an inclined tiltable plate and tilting means therefor, travelling retarding means mounted to move on the plate and disposed to retard the rolling movement of material deposited thereon whereby other than freely rolling 55 objects may be brought to rest on the plate, a movable mounting for the retarding means and plate tilting means, the tilting means being disposed at a spaced interval behind the retarding means, and means operable to return the 60 plate to its original position.

2. A separator of the character described comprising, an inclined tiltable plate and tilting means therefor, travelling retarding means

mounted to move over the plate and disposed to retard the rolling movement of material deposited thereon whereby other than freely rolling objects may be brought to rest on the plate, material feeding means, a transfer device inserted 5 between the feeding means and plate and having pockets formed therein disposed to register alternately with the feeding means and plate to alternately receive material from the feeding means and discharge on to said plate, actuating 10 means for the transfer device, a movable mounting for the retarding means, plate tilting means, and transfer actuating means, the transfer actuating means being disposed at a spaced interval behind the retarding means, and the plate tilting 15 means being disposed at a spaced interval behind the transfer actuating means, and means operable to return the plate to its original position.

3. In a separator of the character described, 20 the combination of a laterally inclined supporting platform, a travelling belt operable over the platform in parallel relation to its lower edge and adjacent thereto, a rotatable cylindrical member disposed adjacent the belt with its axis in parallel relation to the lower edge of the belt and having radially arranged plates disposed longitudinally therein to extend from its axis to its periphery to form pockets, a segmental shield member disposed over each pocket with its longer 25 edges spaced from the adjacent plates to form intervening passages, an overhanging flexible lip member mounted on the lower edge of the platform and underlying the belt to slidably engage the shields and register with alternate passages 30 to introduce material therethrough, and material receiving means mounted adjacent the cylinder on the side opposite the lip to register with other alternate passages to receive material therefrom.

4. A separator for separating freely rolling material from non-rolling material in a mixture of the two types of material comprising, feeding means for the mixture of material, a pair of aligned inclined tiltable plates adjacent the feeding means to receive the mixture, the inclination of said plates being such that the nonrolling material will be retained on the plates and the freely rolling material will tend to pass downwardly over the plates, travelling retarding means 45 mounted over the plates and moving thereover in a downward direction at such a speed that the material fed to the inclined plates will be retarded in its natural movement, uniformly movable means mounting the retarding means to produce a constant movement of said retarding means, tiltable means for said tiltable plates mounted on said movable mounting means and positioned at spaced intervals behind said retarding means and operable to tilt the uppermost plate of the pair when the retarding means 50 overlies the lowermost plate of the pair to thus discharge the non-rolling material, and means operable to return the plates to their normal 55 inclined position.

JAMES DOTTO.
